UNITED STATES PATENT OFFICE.

CHARLES F. PATTERSON, OF NEW YORK, N. Y.

SPRINKLER SUPERVISORY SYSTEM.

1,090,497.

Specification of Letters Patent. Patented Mar. 17, 1914.

Application filed August 1, 1912. Serial No. 712,739.

To all whom it may concern:

Be it known that I, CHARLES F. PATTERSON, a citizen of the United States of America, and a resident of New York, in the county of New York and State of New York, have invented certain new and useful Improvements in Sprinkler Supervisory Systems, of which the following is a specification.

10 My invention relates to sprinkler supervisory systems, such as are employed for supervising the condition and operation of fire-protection sprinkler systems.

My invention is particularly applicable 15 to systems of the dry-pipe type, *i. e.*, sprinkler systems in which normally there is no water in the risers and branch pipes leading to the sprinklers. In such systems there is usually, between the riser and the supply 20 main, a check valve; and customarily, sufficient air pressure is maintained, or intended to be maintained, above this check valve, to prevent water passing the check valve and entering the riser above said 25 valve. Customarily, in order to avoid high air pressures above the check valve, said valve is a double-seat valve having an upper valve portion, and a lower valve portion, adapted to seat simultaneously against separate 30 seats, the upper valve portion being very much larger than the lower valve portion, the valve acting as a differential piston so that a relatively low pressure on the upper side of the valve counter-balances a 35 relatively high pressure on the underside of the valve. In such a system, in case one of the sprinklers open, it releases the air pressure above the check valve, and the latter then opens, water flows up through the 40 riser and into the sprinkler branches, and out through the sprinkler or sprinklers which may have opened.

In practice, water very frequently leaks slowly past the valve, and accumulates above 45 the valve in such quantity, that the weight of the water above this valve interferes greatly with prompt opening of the valve. It is, therefore, desirable to provide automatic indication of the presence of any considerable quantity of water above the valve.

It is further desirable to provide automatic indication of the flow of water in any considerable quantity past the valve, as flow of any considerable quantity is due in al-

most all cases, to the opening of one of the 55 sprinklers, and constitutes presumptive evidence of the existence of a fire.

In the system herein described, I provide means for indicating when any considerable flow of water past the check valve occurs, 60 and for sending in an alarm signal when such considerable flow occurs. The system therefore constitutes in effect an automatic fire alarm system. I also provide other means for indicating the presence of any 65 considerable quantity of water above the valve, and for sending a trouble signal in the event of the presence of any considerable quantity of water above the valve; the trouble signal being sent when one of the 70 sprinklers opens, but being also sent when water exists in any considerable quantity above the valve, for any other reason, for example, the existence of a small leak.

The valve very often becomes corroded in 75 its seat, and so is held from opening when the pressure above the valve decreases. It is, therefore, desirable to have means which shall indicate material fall in pressure above the valve. In case the fall in pressure is 80 due to a small leak, as sometimes happens, the fall in pressure will be small at first, and therefore in the present system I provide pressure-operated means which will send a trouble signal in case the pressure 85 falls slightly below normal. In case a sprinkler opens there is an immediate great fall in pressure, followed instantly (if the valve opens) by an immediate great increase in 90 pressure, due to the flow of water, under the pressure of the supply main, past the check valve and up through the riser. Therefore, in my system I provide means for sending in a fire signal in the event of great increase above the normal pressure in the 95 riser.

My invention comprises means for indicating relatively great flow of water past the valve; means for indicating presence of a less amount of water above the valve; 100 means for indicating a fall in pressure above the valve; and means for indicating a rise in pressure above the valve.

Other features of my invention will be pointed out hereafter.

The objects of my invention are to increase the effectiveness of supervision of 105 sprinkler systems, particularly dry-pipe

sprinkler systems, to provide for indication of rapid flow of water past the check valve of such systems, to provide for separate indication of relatively slow flow of water past such valve, or the presence of water in more than negligible quantity above such valve, to provide for indication of slight fall of pressure above the valve, and for separate indication of rise of pressure above the valve, and in general, to make the apparatus simple, reliable and effective.

I will now proceed to describe my invention with reference to the accompanying drawings and will then point out the novel features in claims.

In the drawings: Figure 1 shows more or less diagrammatically an elevation and partial section of a sprinkler system having one form of my improved supervision system connected thereto. Fig. 2 is a view similar to Fig. 1 showing alternative means for indicating rise of water above the valve. Fig. 3 is a further view similar to Fig. 1, but illustrating further alternative contact means adapted to indicate slight fall in pressure above the valve, great fall in pressure above the valve, and increase in pressure above the valve.

Referring first to Fig. 1, numeral 1 designates a riser of a dry-pipe sprinkler system, numeral 2 designates a differential check valve of ordinary type normally preventing entrance of water from supply pipe 3 to riser 1; 4 designates one of the sprinkler branches and 5, 5 designates sprinklers.

6 designates a manifold having connections 7, 7 at points of different level to the riser 1. 8 designates a float-actuated contact device the float of which is in the lower portion of said manifold, and 9 designates another float-actuated contact device, the float of which is in the upper portion of said manifold. The particular construction of the float-actuated contact devices illustrated is unimportant, though the particular construction illustrated is convenient, the float rod being supported by a flexible diaphragm 10 which also serves to close the manifold. To support the floats when the latter are not supported by water in the manifold, perforated partitions 11 are provided.

13 designates a pressure-actuated contact device connected by a tube 13^a to the manifold 6. The particular construction of pressure actuated contact device shown comprises a Bourdon tube, but any other suitable type of pressure-actuated contact device may be substituted therefor.

14 designates the actuating magnet of a trouble-signal-transmitter, 15 the armature thereof, and 16 the break wheel thereof. The construction and manner of operation of such transmitters is well known and it is not deemed necessary to illustrate same in detail here.

17 designates the actuating magnet of an alarm transmitter, 18 the armature thereof, and 19 the break wheel thereof.

In the circuit arrangements shown, each transmitter magnet is located in a normally-closed circuit comprising a current generator or battery, 20 in the case of transmitter 14, and 21 in the case of transmitter 17. Each transmitter magnet is arranged to be deenergized by the closing of a short across the magnet terminals, by one or another of the contact devices before mentioned.

Float-actuated contact device 8 is arranged, when the float is raised, by water in the manifold, to bring together contact points 22 and 23, thereby closing a short across the terminals of magnet 14. Pressure-actuated contact device 13 is arranged, upon slight decrease in pressure in the manifold, to bring together contact points 24 and 25, thereby also closing a short across the terminals of magnet 14. It will be clear that transmitter 14 will be operated upon the closing of a short either by contact device 8 and contact points 22 and 23, or by contact device 13 and contact points 24 and 25.

Float-actuated contact device 9 is arranged, when its float is raised by water within the manifold, to bring together contact points 26 and 27, and thereby to close a short across the terminals of magnet 17. Pressure-actuated contact device 13 is arranged, upon increase in pressure in the manifold above the normal pressure therein, to bring together contact points 28 and 29, thereby also closing the short across the terminals of magnet 17. It will be clear that transmitter 17 will be caused to operate upon the closing of a short across its terminals, either by contact device 9, or by contact device 13.

The operation of this system is as follows: Supposing one of the sprinklers 5 to open, and so to cause a great decrease in pressure above the check valve 2, said valve will normally open, and the water from supply main 3, flowing rapidly past said valve, will flow up through the riser 1 to the sprinkler branch 4, and sprinkler or sprinklers 5, and in so doing will also flow into manifold 6, through the lower connection 7, actuating both of the float-actuated contact devices, and also actuating the pressure actuated contact device 13; because, the water in the supply main being under much greater pressure than the air pressure normally existing in the riser 1, when water flows freely past the valve it soon raises the pressure in the riser and in the manifold 6 far above the pressure normally existing in said riser and manifold. The contact device 9 and the contact device 13 therefore each close a short across the terminals of an alarm transmitter magnet 130

17, thereby causing an alarm signal to be transmitted. The rise of water in the manifold also actuates the trouble contact device 8, causing the trouble signal transmitter to operate; and such practically simultaneous operation of transmitters 14 and 17 is important, since the operation of transmitter 17 alone, though in general an indication of serious trouble, might be due merely to the pumping up of excessive air pressure in riser 1; but the sending in of alarms from both transmitters 14 and 17, simultaneously or in quick succession, is a positive indication of the blowing of a sprinkler head, or the development of a very great leak in the system such as requires immediate attention to prevent damage from water flow; for these two signals, coming in simultaneously or nearly so, indicate that water has risen in the riser 1 so rapidly as to operate both float contact devices 8 and 9 at nearly the same instant, or to operate both float contact device 8 and pressure operated contact device 13 at nearly the same instant, and this can occur only through excessive water flow such as is due to the blowing of a sprinkler head (usually occasioned by a fire) or to the development of an excessive leak. The simultaneous or nearly simultaneous sending of signals by transmitters 14 and 17 cannot well be due to the mere pumping up of excessive pressure in riser 1, for even if there had been a slow leak, prior to the pumping up of such excessive pressure, such that water had nearly risen to the point of operating contact device 8 before excessive pressure was pumped up in riser 1, the pumping up of such excessive pressure in itself tends to retard further leakage into the riser, so that under practically no conditions can transmitters 14 and 17 send in their signals simultaneously or nearly so, except upon the blowing of one or more of the sprinkler heads or the development of an excessive leak. Since either contact device 9 or contact device 13 will close a short across the terminals of magnet 17 in the event of rapid flowing of water into the riser 1, the sending of an alarm by transmitter 17 is made doubly certain.

In case water should accumulate slowly above the check valve 2, because of a small leak in said valve, or because of condensation in the riser, or for any other reason, the contact device 8 will be actuated and will cause the trouble-signal transmitter 14 to operate. In case pressure should fall slowly in the riser 1, due to an air leak in the system, pressure actuated contact device 13 will operate contact points 24 and 25, and so will close a short across the terminals of magnet 14, causing said transmitter to send in a trouble signal. Ordinarily, pressure-actuated contact device 13, and contact points 24 and 25, will be so adjusted that, upon slight

decrease in pressure in the riser, contact points 24 and 25 will be brought together, and the trouble-signal transmitter 14 operated, before the pressure above the check valve has decreased to such extent as to permit such check valve to open and to permit contact device 8 to operate; it being the common practice, in dry-pipe systems, to maintain above the check valve an excess of pressure above that required to hold the valve 2 seated normally.

In the arrangement shown in Fig. 2, I provide, in lieu of the upper flow-actuated contact device 9, a flexible diaphragm 30 in the manifold 6, and contact points 31 and 32 arranged to be actuated by rise of this diaphragm; said contact points 31 and 32 arranged, when brought together, by the rise of the diaphragm, to close a short across the terminals of alarm-transmitter magnet 17. This diaphragm 30 will be operated by rise of water in the manifold 6, such rise of water increasing the pressure upon the lower side of the diaphragm. In other respects the arrangement shown in Fig. 2 is the same as the arrangement shown in Fig. 1, and the operation of the system shown in Fig. 2 is the same as the system shown in Fig. 1.

In the arrangement shown in Fig. 3, the pressure actuated contact device 13 is provided with contact points so arranged that the fire-alarm transmitter 17 is operated either in the event of a material increase of pressure, or in the event of a great decrease in pressure; and is also provided with contact means whereby the trouble alarm transmitter 14 is actuated in the event of slight decrease in pressure. To this end, said pressure-actuated contact device 13 is provided with two contact points, 33 and 34, in the energizing circuit of magnet 14, which contacts are closed upon slight decrease in pressure, so closing a short across the terminals of magnet 14 and so causing the transmitter to which that magnet belongs to operate. Said contact device 13 is further provided with contact springs 35 and 36, which are brought together in the event of a further decrease in pressure, thereby closing a short across the terminals of fire alarm transmitter magnet 17, and causing transmitter 17 to send in an alarm. And said contact device 13 is further provided with contact points 28 and 29 which are brought together in the event of a material increase in pressure. With this arrangement, in case one of the sprinklers 5 opens, but the valve 2, for any reason, does not open, the great decrease in pressure due to the release of air pressure by the open sprinkler 5, will cause contact device 13 to operate contact springs 35 and 36, thereby causing fire alarm transmitter 17 to operate and to send in a fire alarm even though the valve 2 has not opened. In other respects the operation of the system is the

same as that of arrangements illustrated in Figs. 1 and 2; the effect of the separation of contact points 33 and 34, in Fig. 3, being the same as the effect of the closing of contact between points 24 and 25 in Figs. 1 and 2. In Fig. 3 I also show the lower float as normally supported by a small body of water in the manifold 6, the intention being that the level of water in the manifold and 10 in the riser, shall be at about the level of the lower connection 7. Any rise of the water level above this point, will, as previously explained, bring together springs 22 and 23 and give a trouble alarm. I have also 15 shown in Fig. 3 other contacts 37 and 38, which will be closed by the contact device 8 in case the float should drop below normal position for any reason, as for example, collapse of the float or a leak therein. These 20 contact points 37 and 38 when so brought together close a short around the magnet 14, so giving a trouble alarm.

What I claim is:—

1. The combination with a dry-pipe 25 sprinkler system comprising a liquid supply main and a riser provided with sprinklers connected thereto, of a check valve between the supply main and riser, means including signal-transmitting means for indicating rise of level of liquid in the riser above said check valve, and means including signal-transmitting means for indicating increase of pressure above normal in the riser above said check valve, whereby indication of material flow through said riser will be given by the combined operation of said level-actuated and pressure-actuated signal-transmitting means.

2. The combination with a dry-pipe 40 sprinkler system comprising a liquid supply main and a riser provided with sprinklers connected therewith, of a check valve between the supply main and riser, means actuated by rise of level of liquid, unaccompanied by 45 material increase of pressure, in the riser above the check valve, means operated by increase of pressure above normal in the riser, and separate signal-transmitting means arranged one to be operated by said 50 level actuated means, the other to be operated by said pressure-actuated means, whereby indication of material flow through said riser will be given by the combined operation of said separate signal-transmitting means.

3. The combination with a dry-pipe 55 sprinkler system comprising a liquid supply main and a riser provided with sprinklers connected thereto, of a check valve between the supply main and riser, means including signal-transmitting means for indicating material increase in pressure above normal in the riser above said check valve, means including other signal-transmitting means for 60 indicating decrease in pressure below nor-

mal in said riser, and means actuated by rise of liquid in the riser above the check valve arranged to actuate the former of said signal transmitting means, whereby indication of material flow will be given by the 70 substantially simultaneous operation of said signal transmitting means due to a decrease in pressure in the riser above the check valve followed immediately by material increase in pressure or rise of liquid level in said 75 riser.

4. The combination with a dry-pipe 80 sprinkler system comprising a liquid supply main and a riser provided with sprinklers connected thereto, of a check valve between the supply main and riser, means including signal transmitting means for indicating material increase in pressure above normal in the riser above said check valve, means including other signal transmitting means for indicating decrease in pressure below normal in said riser, and means actuated by rise of liquid in the riser above the check valve arranged to actuate the latter of said signal transmitting means, whereby indication of material flow will be given by the substantially simultaneous operation of said signal transmitting means due to a decrease in pressure or a rise of level of liquid in the 85 riser above the check valve, followed immediately by a material increase in pressure in said riser.

5. The combination with a dry-pipe 90 sprinkler system comprising a liquid supply main and a riser provided with sprinklers connected therewith, of a check valve between the supply main and riser, a plurality of contact devices arranged to be actuated independently by rise of liquid to different heights in the riser above said check valve, and signal transmitting means operated by said contact devices, whereby indication of material flow through said riser will be given by the successive actuation of said 95 contact devices.

6. The combination with a dry-pipe 100 sprinkler system comprising a liquid supply main and a riser provided with sprinklers connected therewith, of a check valve between the supply main and riser, two float-actuated contact devices arranged to be actuated independently by rise of liquid to different heights in the riser above said check valve, and separate signal-transmitting means arranged to be operated the one by one of 105 said float-actuated devices, the other by the other of said float-actuated devices, whereby indication of material flow through said riser will be given by the successive actuation of said separate signal-transmitting 115 means.

7. The combination with a dry-pipe 120 sprinkler system comprising a liquid supply main and a riser provided with sprinklers connected therewith, of a check valve between 125

- the supply main and riser, two float actuated devices arranged to be actuated by rise of liquid to different heights in the riser above the check valve, and pressure-operated means likewise connected to the riser of said sprinkler system, and arranged to be operated by increase in pressure in the riser, and signal-transmitting means operated by said float-actuated and pressure-actuated devices, whereby indication of material flow through said riser may be given by the successive actuation of said float actuated devices, and by the combined operation of said pressure-actuated and float-actuated device.
8. The combination with a dry-pipe sprinkler system comprising a liquid supply main and a riser provided with sprinklers connected therewith, of a check valve between the supply main and riser, two contact devices, arranged to be actuated by rise of liquid in the riser, and located at different heights, and separate signal-transmitting means arranged to be operated the one by one of said contact devices, the other by the other of said devices, and pressure operated means likewise connected to the riser of said sprinkler system, and arranged to be operated by increase in pressure in the riser, said pressure-actuated means arranged when actuated to operate the same signal transmitting means which is arranged to be operated by the upper of said contact means.
9. The combination with a dry-pipe sprinkler system comprising a liquid supply main and a riser provided with sprinklers connected therewith, of a check valve between the supply main and riser, two contact devices, arranged to be actuated by rise of liquid in the riser, and located at different heights, and separate signal-transmitting means arranged to be operated, the one by one of said contact devices, the other by the other of said contact devices, and pressure operated means likewise connected to the riser of said sprinkler system, and arranged to be operated by decrease in pressure in the riser, said pressure-actuated means arranged when actuated to operate the same signal transmitting means which is arranged to be operated by the lower of said contact means.
10. The combination with a sprinkler system, of pressure-actuated means, and two signal-transmitting devices controlled thereby, said pressure-actuated means arranged to operate one of said signal-transmitting means in the event of material increase of pressure, and in the event of great decrease in pressure, and to operate the other of said signal-transmitting means in the event of slight decrease in pressure in the system, whereby upon a great decrease in pressure below normal in the system, or upon a material decrease in pressure below normal followed immediately by a material increase in pressure above normal in the system, both of said signal transmitting means will be operated substantially simultaneously and indication of flow will thus be given.
11. The combination with a dry-pipe sprinkler system comprising a liquid supply main and a riser provided with sprinklers connected therewith, of a check valve between the supply main and riser, pressure-actuated means, and two signal-transmitting devices controlled thereby, said pressure-actuated means arranged to operate one of said signal-transmitting means in the event of material increase of pressure in the riser, and in the event of great decrease in pressure in the riser, and to operate the other of said signal-transmitting means in the event of slight decrease in pressure in the riser, and two devices, arranged to be actuated by rise of liquid in the riser, and located at different heights, the higher of said devices arranged when actuated to actuate that signal transmitting means which is operated by said pressure-actuated means upon material increase in pressure or great decrease in pressure, the lower of said devices arranged when operated to actuate that signal transmitting means which is operated by the pressure-operated means upon slight decrease in pressure.

In testimony whereof I have signed this specification in the presence of two subscribing witnesses.

CHARLES F. PATTERSON.
